FIG.1

FIG.2

FIG.3

FIG.5

FIG.4

FIG. 6

FIG. 1 is a front elevational view of a chair, showing my new design;

FIG. 2 is a side elevational view thereof, the diametrically opposite side being substantially a mirror image thereof;

FIG. 3 is a top plan view thereof;

FIG. 4 is a bottom plan view;

FIG. 5 is a rear elevational view; and

FIG. 6 is a bottom perspective view thereof.

I claim:

The ornamental design for a chair, as shown and described.
